Primary Examiner — Cynthia R Underwood**CLAIM**

The ornamental design for a hanger dispenser, as shown and described.

DESCRIPTION

FIG. 1 is a front elevational view of a hanger dispenser showing my new design;

FIG. 2 is a rear elevational view thereof;

FIG. 3 is a left elevational view thereof;

FIG. 4 is a right elevational view thereof;

FIG. 5 is a bottom plan view thereof;

FIG. 6 is a top plan view thereof;

FIG. 7 is a bottom rear perspective view thereof;

FIG. 8 is a top front perspective view thereof;

FIG. 9 is a top front perspective view of my new design shown in an upward alternate position of use; and,

FIG. 10 is a top front perspective view of my new design shown in a downward alternate position.

The broken lines showing the connector are included for the purpose of depicting environmental structure and form no part of the claimed design.
